UNITED STATES PATENT OFFICE.

EDWARD CARROLL, OF CLAY, MISSOURI.

WINKER-BRACE FASTENER.

SPECIFICATION forming part of Letters Patent No. 732,617, dated June 30, 1903.

Application filed December 30, 1901. Serial No. 87,782. (No model.)

To all whom it may concern:

Be it known that I, EDWARD CARROLL, a citizen of the United States, residing at Clay, in the county of Adair and State of Missouri, have invented a new and useful Winker-Brace Fastener, of which the following is a specification.

This invention relates to winker-brace fasteners.

10 The object of the invention is to provide a separable connection for the winker and winker-brace strap which may be readily disconnected, but is securely held together under ordinary circumstances.

5 It is a well-known fact that a horse when tied is apt to become impatient and will rub his head against anything within his reach, and the prominence of the winker-blind and its connection makes it especially liable to 20 such violence, and the breaking of the fly-strap or winker-brace is the consequence. This invention is designed to obviate this difficulty by providing a separable connection between the fly-strap and the blind, so that 25 when the animal rubs his head the connection will separate instead of breaking, as is the case in the ordinary bridle.

Figure 1 represents a perspective view of a bridle, showing this improved device applied thereto. Fig. 2 represents a side elevation of the inside of a winker, showing a portion broken out and the two members of this device connected therewith, the outer member being shown in section and connected to a fly-strap. Fig. 3 represents detail views of the two members detached from the bridle and from each other. Fig. 4 represents a transverse section of a winker-brace having this device applied.

40 The same reference-numerals indicate corresponding parts in all the figures.

In the drawings a bridle-blind 10 is shown provided with a plug 20, preferably made of

metal and cylindrical in shape, having an enlarged flattened lower end provided with perforations, as 21, therein and also provided with a larger perforation or aperture 22 for receiving a rivet 23 for securing it more firmly to the blind. The perforations, as 21, are designed for stitching the plug between the layers of the blind. A thimble 30, also preferably made of metal and of a size adapted to fit tightly over the plug 20, is provided throughout its length with an exterior flange 31, provided with longitudinally-alined perforations, as 32, for stitching or otherwise attaching it to the fly-strap.

The device is shown at the left of Fig. 1 detached ready for connecting the fly-strap to the blind. As shown at the right of said figure, the thimble 30 is shown fitted down over the plug and the fly-strap attached to the blind. The frictional contact of the two members is sufficient to hold them tightly together unless jerked or pulled off, and to connect them it is simply necessary to push the thimble 30 down over the plug 20.

This attachment is simple in construction, cheap to manufacture, and may be applied to any bridle already in use by any one having a suitable needle and thread.

I claim as my invention—

A winker-brace fastener comprising a tubular member having a longitudinal exterior flange provided with perforations therein, and a socket member adapted to fit in said tubular member and provided with perforations at its lower end.

In testimony that I claim the foregoing as my own I have hereto affixed my signature in the presence of two witnesses.

EDWARD CARROLL.
